UNITED STATES PATENT OFFICE.

MARINO BELLO, OF HIGHLAND PARK, ILLINOIS.

DESIGN FOR A BATTERY CONTAINER.

Application filed March 11, 1925. Serial No. 12,680. Term of patent 7 years.

To all whom it may concern:

Be it known that I, MARINO BELLO, a subject of the King of Italy, residing at Highland Park, county of Cook, and State of Illinois, have invented a new, original, and ornamental Design for Battery Container, of which the following is a specification, reference being had to the accompanying drawing, forming a part hereof, in which:

The drawing shows the battery container in perspective.

I claim:

The ornamental design for a battery container, as shown.

MARINO BELLO,
